PRESERVATIVE CLOSURE

James W. Case, Fairfax, Va.

Application October 29, 1954, Serial No. 465,760

6 Claims. (Cl. 138—96)

(Granted under Title 35, U. S. Code (1952), sec. 266)

The invention described herein may be manufactured and used by or for the Government of the United States of America for governmental purposes without the payment of any royalties thereon or therefor.

This invention relates to closures and more particularly to preservative closures for protecting portions of coupling members prior to actual coupling engagement. Examples of such coupling members are the many openings provided in various ordnance equipments which are adapted to receive fuzes, detonators and other components in the field. In many cases the ordnance items are stored for a considerable period of time or are transported throughout the world under varying and extreme climatic conditions before attachment of the components and assembly is made. It is therefore of the utmost importance that the coupling members of the ordnance items be protected from the many weather conditions during the period to prevent rusting and surface corrosion.

The invention has been found particularly adaptable for closing and preserving fuze hole threads of projectiles, bombs and the like. In such instances the preservative closure is inserted into the opening immediately after the machining operation and thus protects the threads from rust during shipment of the empty projectile case to an ammunition plant where explosive loading operations are performed. At this point a readily separable bottom of the closure member may be "punched out" or removed, allowing loading of the powder through the opening with the threads being protected by the remaining wall of the closure member. This is a very important advantage since the accumulation of powder in the threads creates an extremely hazardous condition and the removal of same is obviously a slow and tedious procedure.

Heretofore, it has been the practice to cover such coupling members with heavy layers of grease or to spray thick coatings of plastic material thereon. However, these methods were not found to be satisfactory since the laborious and time consuming operation of either degreasing or stripping was required before the coupling members could be assembled. In ordnance items where the assembly time prior to use may be a critical factor in the success or failure of a military operation, such delay may be fatal.

In accordance with this invention a pliable disposable preservative closure is provided which may be quickly inserted and removed from a coupling member. The preservative closure has a contour which is designed closely to engage the specific coupling means which is to be protected and is formed from a material having a slight exudation of oil therefrom, adequate to prevent corrosion of the engaged surfaces. In the embodiment illustrated the bottom of the preservative closure is shown joined to the side wall by a relatively weak marginal portion so that the bottom may easily be removed allowing filling of a projectile or the like through the opening if such is desired while the wall remains to protect the coupling

2

means. Thus, a preservative closure is provided which may be quickly applied, gives adequate protection during its insertion period and is quickly removed.

It is accordingly an object of the invention to provide 5 an inexpensive readily applied and removed preservative cover for a coupling member.

A further object is to provide a disposable preservative member which functions both to seal a coupling opening and also to protect the specific coupling means there- 10 in from rust and corrosion.

A further object is to provide a pliable preservative closure which is quickly insertable within a coupling opening, provides close engagement with every portion of the coupling means located within the opening during the 15 insertion period to protect against rust and corrosion thereof, and is readily detachable from the opening leaving the opening and coupling means free and clear for subsequent coupling action.

Other objects and many of the attendant advantages 20 of this invention will be readily appreciated as the same becomes better understood by reference to the following detailed description when considered in connection with the accompanying drawings wherein:

Fig. 1 is an enlarged transverse sectional view of the 25 present invention; and

Fig. 2 is a side elevational view of a projectile, broken away at its nose portion to show a threaded fuze opening with the preservative closure inserted therein.

Considering first Fig. 1 the preservative closure member 10 is shown as a centrally hollow cup-shaped plug having a cylindrical externally threaded wall 11, a circular bottom 12 and a peripheral flange 13. In the embodiment illustrated the circular bottom 12 is shown joined to the wall 11 by a weakened marginal portion 14 which permits ease in removal of the bottom if such is desired.

In the embodiment illustrated the preservative closure is composed of a thermoplastic resin material which has as one of its characteristics that of being soft and pliable. For example, such plasticized resins as polyvinyl chloride or polyethylene have proven satisfactory. It has also been found that these resins containing approximately 7% of a rust inhibitor oil therein offer a most desirable preservative property. There are several rust inhibitor oils provided commercially which will suffice such as 40 those containing between 3-7% of sulfonic or carboxylic acid or their metallic salts. It is to be understood that other materials may be suitable and the above percentage of oil dispersed within the material is not critical provided that the material is pliable, the material and the oil, in 45 mechanical mixture forms a physically stable compound. Thus it will be understood that in this mechanical mixture the oil is one chemical compound and the resin is the other chemical compound, and the quantity of oil is sufficient to produce a constant exudation of the oil from the 50 material.

In Fig. 2 the preservative closure is shown inserted in a threaded opening 15 in the nose of a hollow projectile 16. It is to be noted that the threads on the cylindrical wall of the closure snugly mate with those of the opening 60 over the entire threaded area of the opening thereby completely sealing the threads and causing same to be continually covered with the oil exuding from the material. Also the underside of the peripheral flange 13 of the closure member is firmly seated on and covers the flat nose portion 17 adjacent the threaded opening thus protecting 65 and sealing same. In inserting the closure member in the opening it is not necessary that it be screwed into place, a lengthy operation. Since the member is pliable it is simply pushed into full inserted position, the threads 70 on the cylindrical wall quickly adjusting themselves into proper mating relationship with the threads in the opening. If it is desired to fill the interior of the projectile

the bottom 12 may be quickly punched out or removed leaving the side wall to protect the threads of the opening during the filling operation.

Obviously many modifications and variations of the present invention are possible in the light of the above teachings. It is therefore to be understood that within the scope of the appended claims the invention may be practiced otherwise than as specifically described.

What is claimed is:

1. A preservative closure for sealing and lubricating coupling means within an opening comprising; a cup-like member molded of Vinylite resin having thereon coupling means complementary with the entirety of that to be protected within the opening and having dispersed therein a rust inhibitor oil in a strength sufficient to produce slow exudation of said oil from the member.

2. A screw thread protector comprising a pliable, threaded body snugly mateable with the entire length and depth of the threads to be protected, said body being molded of Vinylite resin having dispersed in mechanical mixture therein a rust inhibitor oil in a strength sufficient to produce slow exudation thereof from the body.

3. A thread protector comprising, a body of molded Vinylite resin having preformed screw threads for snug engagement with the entire length and depth of the threads to be protected and having dispersed therein a rust inhibitor oil in a strength sufficient to produce slow exudation of oil from the body.

4. A preservative closure for a threaded opening comprising, a plug molded of Vinylite resin externally threaded for snug engagement with the entire length and depth of the threads of the opening and having dispersed therein a rust inhibitor oil in sufficient quantity to produce slow exudation of oil from the plug.

10

15

20

25

30

5. A device for protecting thread surfaces from corrosion and abrasion comprising a pliable threaded body snugly mateable with the entire length and depth of the thread surfaces to be protected, said body being molded of plasticized stabilized resin having a rust inhibitor oil dispersed therein in a mechanical mixture and a quantity sufficient to produce slow exudation of oil from the body, said body being sufficient pliable to permit the device to be manually rammed into thread protecting position and manually removed therefrom without bodily rotation.

6. A preservative closure for a screw threaded opening comprising a hollow cup-shaped plug molded of Vinylite resin and having dispersed in mechanical mixture therein a rust inhibitor oil in sufficient quantity to produce slow exudation of oil, said plug being externally screw threaded for snug engagement with and throughout the entire surface of the threads of the opening, and having pliable walls whereby the plug may be forced into or out of the opening without bodily rotation.
